Primary Examiner — Katherine Glennon

(57) **CLAIM**

The ornamental design for a wrist watch, as shown and described.

DESCRIPTION

1.1 is a front perspective view of a wrist watch, showing my new design;

1.2 is a front view thereof;

1.3 is a back view thereof;

1.4 is a right-side view thereof;

1.5 is a left-side view thereof;

1.6 is a top view thereof;

1.7 is a bottom view thereof; and

The dashed lines in the reproductions show portions of the wrist watch that form no part of the claimed design.

1 Claim, 7 Drawing Sheets
